Primary Examiner — Karen E Eldridge Powers(74) *Attorney, Agent, or Firm* — Suzanne Kikel, Patent Agent(57) **CLAIM**

The ornamental design for a powered toilet bowl brush, as shown and described.

DESCRIPTION

FIG. 1 is a top, rear, and right side perspective view of a powered toilet bowl brush, showing my new design.

FIG. 2 is a top, front, and left side perspective view of the powered toilet bowl brush of FIG. 1 positioned in a toilet bowl.

FIG. 3 is a bottom perspective view of the powered toilet bowl brush of FIG. 1.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a bottom plan view thereof; and,

FIG. 9 is a top plan view thereof.

The broken lines showing a toilet bowl in FIG. 2 depict environmental subject matter and form no part of the claimed design.
